PROCESS OF IMPROVING MOTOR FUELS

John C. Geniesse, Ridley Park, and Raymond Reuter, Philadelphia, Pa., assignors to The Atlantic Refining Company, Philadelphia, Pa., a corporation of Pennsylvania

Application March 9, 1928, Serial No. 260,342

17 Claims. (Cl. 196—50)

The present invention relates to the improvement of fuels from the standpoint of anti-detonation, for general use in internal combustion motors, and especially in those having high compression; and more particularly our invention relates to a method for producing a fuel of increased anti-detonating qualities from a hydrocarbon oil with properties comparable with those of ordinary commercial gasoline.

10 Heretofore various methods have been proposed for decreasing the detonation effect, or what is ordinarily termed "knocking", in the use of the ordinary motor fuels in internal combustion engines. Methods commonly known for increasing the anti-detonation value of the common motor fuels include those in which various compounds, as, for instance, tetraethyl lead, aniline, benzol, or alcohol are added to the fuels, said fuels having been obtained as the result of one 15 of the recognized methods of distillation of crude petroleum. Likewise, such compounds as mentioned above have been added to the products obtained by cracking various cuts of crude petroleum, for the purpose of increasing their anti-detonation value. In other words, it has been heretofore recognized that fuels having a high anti-detonation value may be produced by the addition of certain substances to the commonly known motor fuels.

20 In accordance with our invention, petroleum distillates of approximately the distillation range of gasoline are subjected to a heat treatment at a relatively high temperature for a comparatively short length of time, for materially increasing the anti-detonation value of the distillate. For example, a straight run gasoline from a Mid-Continent crude oil may by such treatment have its anti-detonation characteristic increased an amount at least equivalent to that obtainable by 25 the addition of 15 parts by volume of benzol to 85 parts of the gasoline. Among the oils whose properties are such as to adapt them for the treatment as hereinafter described is one which, upon condensation immediately after heat treatment by our method yields a condensate, at least 30 95% of which will distil below 43° F., when subjected to the A. S. T. M. distillation test (D86-27). A further example of an oil or distillate with properties suitable for treatment by our process 35 is one of which, when subjected to the aforesaid distillation test, more than 50% or preferably at least 75% thereof will distil below 43° F.

The petroleum distillate to be treated in accordance with our invention is obtained from a 40 hydrocarbon oil by separating the particular dis-

tillate from the components of the oil not within the desired boiling range, by any of the usual distillation methods, or the petroleum distillate to be treated may be obtained by "cracking" or breaking down a fraction of the crude oil resulting from a primary distillation to which the crude oil has been previously subjected. 5

The distillate or fraction of either of the characters just referred to is passed into a heating system of any suitable construction which will 10 cause the fraction or distillate to be brought quickly to a high temperature and will maintain it at such high temperature for a period of time ranging from a few seconds to several minutes, for example for a period of from two seconds to 15 one minute; the particular high temperature as well as the particular length of time depending upon the nature of the oil to be treated.

After the oil has been subjected to the intensive heat treatment it is passed into a condensing apparatus of any suitable type wherein it is liquefied. In particular instances it may be desirable to subject the heat treated oil to a fractionating operation before it is liquefied, the necessity of this step depending largely upon the 20 particular properties of the oil being treated. In most cases it has been found that the change in the boiling range of the oil after it has been subjected to the heat treatment is not appreciable and therefore the step of fractionation is not required. The liquefied product obtained as condensate is then disposed of, as for instance by placing it in storage or by conducting it to a 25 chemical treating plant.

The duration of heat treatment and the temperature at which it is carried out will vary with the oil to be treated and with the increase in anti-detonating value that is to be effected. The lowest temperature limit at which we find it practical to carry out the process herein disclosed is 40 850° F., and the maximum duration of the heat treatment is 10 minutes. A temperature of from about 1000° F. to 1200° F. may be used.

An example of the results attainable by our 45 invention is the following. A straight run fraction from mixed base crude which by A. S. T. M. assay distillation test (D86-27) showed an over point of 144° F., 50% off at 288° F., and 97% off at 43° F., and a dry point of 460° F. has its anti-detonation value increased to an extent equivalent to that obtainable by the addition of 26 parts by volume of benzol to 74 parts of the fraction, 50 by subjecting it to a temperature of 1076° F. for a period of 5.6 seconds. This heat treatment has substantially no effect upon the boiling range, an 55

assay distillation test on the product showing an over point of 135° F., 50% off at 286° F., 97% off at 437° F., and a dry point of 459° F. The amount of high anti-detonation fuel obtained is 5 92% by volume of the amount of the oil subjected to the treatment.

Further, it is to be understood that from a practical viewpoint it may be found desirable to distil over a portion, as, for example, 80% of the volume of the petroleum distillate and then subject the remaining 20%, which constitutes the higher boiling portion and of which more than 50% or preferably at least 75% will distil over below 437° F., to the heat treatment described, thereafter blending at least some of the treated portion with the portion distilled over, to produce a fuel of high anti-detonation value.

The distillate operated upon in accordance with our method, and which may be either a 20 straight run or cracked distillate, or a mixture of them or a mixture of casing head gasoline with one or both of them, may be introduced into our heat treating system either in liquid or vapor phase. Furthermore, our process may be practiced as a stage of a multi-stage system or process in which in an earlier stage the distillate to be operated upon in accordance with our method is produced. Our process may be operated in combination or in continuity with a prior stage in 30 which the distillate to be operated upon is produced. This distillate may be introduced into our treating system in the vapor phase, i. e. without intermediate cooling or condensation.

For an understanding of our invention and for 35 an illustration of one of the various forms our system may take reference is to be had to the accompanying drawing, in which:

Fig. 1 is a diagrammatic illustration of a system for heat treating a distillate in accordance 40 with our invention.

Fig. 2 is a diagrammatic illustration of a system for producing or deriving the distillate to be operated upon in combination and continuity with which the system of Fig. 1 may be utilized.

Referring to Fig. 1, H is a heater of any suitable type, in which the distillate to be operated upon in accordance with our invention is subjected to high temperature for a suitable period of time. In the example illustrated the 45 heater comprises a series of tubes or pipes T disposed in the tube chamber A, whose lower end communicates with a flue a delivering waste gases or products of combustion to a stack, not shown. Into the upper end of the chamber A 50 are discharged from the combustion chamber B the hot gases and products of combustion resulting from burning any suitable fuel, as, for example, oil or gas delivered to the burner b. The oil or distillate to be treated is delivered either in 55 liquid or vapor phase, under any suitable pressure, through the pipe c to the inlet of the tube system T through which it rises, at suitable velocity to procure the desired duration of heat treatment, counter-current to the descending 60 hot gases, and the vapors of the treated oil are discharged through the pipe d controlled by the valve v, into the chamber C which, in the example illustrated, is a vertical fractionating column or tower in which are disposed the vertically 65 spaced fractionating members D of any suitable type, such, for example, as bubbler plates, sieve plates, or equivalent. By suitably adjusting the valve v with respect to the pressure of the distillate entering through the pipe c, the rate of flow 70 through the heating zone is controllable to effect 75

the aforesaid desirable duration of heat treatment. The distillate while in the tube system T is heated to a temperature of the desired order hereinbefore indicated.

The vapors of the treated distillate pass upwardly through the column C, undergoing fractionation as well understood in the art, and pass off from the top of the column through the pipe i controllable by valve v1 to the condenser G cooled by any suitable medium, as water, introduced at j and discharging at k. The condensate, comprising the desired product, a motor fuel of increased anti-detonating characteristic, is delivered through the pipe y controlled by the valve v5 to the flow box J where the stream is divided 15 into any suitable proportions, part flowing through the pipe m to the separator S and the other portion flowing through the trapped pipe z into the top of the fractionating column C through which it descends, counter-current to 20 the rising vapors, as reflux oil. In separator S gases and uncondensed components are drawn off through pipe w controlled by valve v3, and the condensate or desired product is drawn off through pipe x controlled by valve v4 to storage, 25 chemical treating plant or other desired destination.

At the bottom of the column C is provided a pipe f, controlled by valve v6 through which is drawn off the residual oil.

A pipe p, controlled by valve v7 connects with the pipe d and with the condenser G whereby all the vapors from the heater tube system T or any desired portion thereof may be passed directly to the condenser G and the condensate 35 then passed to the pipe m, leading to the separating chamber S, through the pipe m' controlled by valve v2. This permits cutting out or omission of use of the fractionating column C and flow box J, and for this purpose the valves v 40 and v1 are closed, valve v7 opened, v2 opened, and v5 closed.

Delivering into the condenser G is a pipe o, controlled by valve v8 for purposes hereinafter described; and with the pipe c communicate a 45 pipe q controlled by valve v9 and a pipe l controlled by valve v10 for purposes hereinafter described.

Referring to Fig. 2, there is represented generally a preceding stage in combination or in continuity with which the system or stage of Fig. 1 may be utilized. K is a fractionating column having vertically spaced fractionating plates D of any suitable character for fractionating vapors introduced through the pipe e controlled by valve v10, from any type of still or oil heating apparatus. The vapor introduced through the pipe e may be that resulting from a cracking operation, or from a simple fractionating or vaporizing still. The vapors ascend through the column 55 K and pass off through the pipe h controlled by the valve v11 to the partial condenser F in which a portion of the vapor is liquefied. The condensate is returned to the top of the column K as reflux liquid through the pipe n controlled by the 60 valve v12. The reflux liquid descends through the column counter-current to the rising vapors, effecting fractionation, and from the side of the column may be taken off several side streams or fractions through the valve controlled pipes s, t 65 and u. The residual oil is drawn off from the bottom of the column through the valve controlled pipe g.

The uncondensed vapors of the lightest fraction are passed through the pipe l controlled by the 75

valve v_{13} to the pipe c of the system of Fig. 1 in whose tube system T they are raised to the desired temperature and for a period of the orders hereinbefore referred to. The vapors from the system of Fig. 2, constituting the distillate whose anti-detonation characteristic is to be enhanced, are accordingly operated upon in combination or in continuity therewith in the system of Fig. 1, yielding through the pipe x a distillate of improved anti-detonation property.

Or, through the pipe q there may be removed from a point adjacent the top of the column K a liquid fraction passed through the valve v_9 to the pipe c and thence into the system of Fig. 1 where that fraction receives the heat treatment characteristic of our invention. The heat treated vapors of this fraction pass into the condenser G of Fig. 1 into which are also delivered through pipe o from the condenser F of Fig. 2 vapors of the lightest fraction from column K and these are mixed or blended with the vapors of the treated fraction drawn off through the pipe q and after treatment in system T delivered into the condenser G . These blended vapors are condensed in condenser G and drawn off through the pipe x as a liquid condensate of improved anti-detonation characteristic. Of the total distillate drawn off through the pipes h and q , that passing off through h may be of the order of 80% and that through the pipe q of the order of 20%, the smaller proportion being heat treated in accordance with our invention in Fig. 1 and then again blended with the larger portion represented by the vapors passing off through the pipe h . For this operation the valve v_{13} is closed and the vapors from the partial condenser F are passed to the condenser G through the pipe o controlled by the valve v_8 .

The pressure upon the oil while in the tubular system T of Fig. 1 may be anything suitable or desirable. It may be sub-atmospheric, substantially atmospheric, or super-atmospheric, for control of the velocity of the oil through the heating zone for determining the desired duration of application of high temperature.

While our system and method as described in connection with Fig. 1 is an important or essential part of our invention it shall be understood that our invention comprehends also the use of the system and method of the character illustrated by Fig. 1 in combination or in continuity with a method or system of the character illustrated by Fig. 2.

It shall further be understood that our invention is not limited to the particular material, product, temperatures or time periods hereinbefore described both generally, and specifically by way of example, but comprehends also other materials operated upon, products, temperatures, time periods etc. falling within the scope of our appended claims which shall be construed as broadly as possible consistent with the state of the prior art.

By the term gasoline in the specification and appended claims, we mean a petroleum distillate having in general the boiling range of U. S. motor gasoline defined in Technical Paper 323-B of the Bureau of Mines, p. 3, and in particular any petroleum distillate having a dry point of 437° F. as defined in the aforesaid paper.

What we claim is:

1. A process for increasing the anti-detonation characteristic of gasoline, which comprises separating a portion thereof having a lower boiling range, and subjecting the remaining portion of

higher boiling range to a temperature in excess of 850° F., whereby the anti-detonation characteristics of said portion are increased solely by thermal conversion.

2. A process of producing gasoline stock possessing anti-detonating characteristics, comprising, cracking a petroleum oil heavier than gasoline under super-atmospheric pressure, releasing the pressure and primarily separating the naphtha stock produced, secondarily separating, by fractionation, the higher boiling portions of said naphtha stock consisting mainly of hydrocarbons in the gasoline range from the lower boiling portion thereof passing the said separated higher boiling gasoline hydrocarbons through a cracking coil in a vapor phase at temperatures of 900° F. or above, separating the gasoline stock produced containing a high percentage of hydrocarbons possessing anti-detonating characteristics from the products of the last mentioned cracking reaction, and commingling the said separated gasoline stock with the lower boiling hydrocarbons primarily separated from the said naphtha stock to produce an anti-detonating motor fuel.

3. A process for increasing the anti-detonation characteristics of a gasoline which comprises subjecting the gasoline to fractionation to separate it into fractions of higher and lower boiling points, subjecting a higher boiling fraction to a temperature of the order of about 850° F. to 1000° F. whereby the anti-detonating characteristics of said fraction are increased solely by thermal conversion and blending the gasoline fraction thus treated with the untreated portion of the gasoline.

4. A process for increasing the anti-detonation value of a motor fuel which comprises distilling off a portion of the motor fuel, subjecting the remaining portion, whereof more than 50% by volume will distil below 437° F. to heat treatment at a temperature in excess of 850° F. for a period of less than ten minutes, whereby the anti-detonation characteristics of said portion are increased solely by thermal conversion and blending at least some of the heat treated portion with the portion distilled off.

5. A process for increasing the anti-detonation characteristic of a gasoline which comprises separating a portion thereof having a lower boiling range, subjecting the remaining portion of higher boiling range to a temperature in excess of 850° F., whereby the anti-detonating characteristics of said portion are increased solely by thermal conversion and blending the untreated and heat treated portions.

6. A process for increasing the anti-detonation characteristic of a gasoline which comprises separating the larger portion thereof having low boiling range, subjecting the lesser portion of higher boiling range to a temperature in excess of 850° F., whereby the anti-detonation characteristics of said portion are increased solely by thermal conversion and blending the untreated and heat treated portions.

7. A method of producing motor fuel which comprises continuously fractionating vapors derived from petroleum to produce gasoline fractions of different boiling ranges, and continuously passing that of said last named fractions having the higher boiling range through a heating zone for such period to raise it to a temperature of upwards of 850° F. to thereby materially increase the anti-detonation characteristic thereof solely by thermal conversion and thereafter blending

- the fraction so treated with the other of said motor fuel fractions.
8. A process for producing a motor fuel having high anti-detonating qualities which comprises separating gasoline into lighter and heavier fractions, subjecting at least one of said heavier fractions to heat treatment at a temperature in excess of 850° F. whereby the anti-detonation characteristics of said fraction are increased solely by thermal conversion and blending the fraction so treated with gasoline.
9. A process for producing a motor fuel having high anti-detonating qualities which comprises separating gasoline into lighter and heavier fractions, subjecting at least one of said heavier fractions to heat treatment at a temperature in excess of 850° F. for a period of less than ten minutes, whereby the anti-detonation characteristics of said fraction are increased solely by thermal conversion and blending the fraction so treated with gasoline.
10. A process for producing a motor fuel having high anti-detonating qualities which comprises separating gasoline into lighter and heavier fractions, subjecting at least one of said heavier fractions to heat treatment at a temperature in excess of 850° F., whereby the anti-detonation characteristics of said fraction are increased solely by thermal conversion, and blending the fraction so treated with a gasoline fraction to form gasoline.
11. A process for producing a motor fuel having high anti-detonating qualities which comprises separating gasoline into lighter and heavier fractions, subjecting at least one of said heavier fractions to heat treatment at a temperature of excess of 850° F. for a period of less than ten minutes whereby the anti-detonation characteristics of said fraction are increased solely by thermal conversion, and blending the fraction so treated with a gasoline fraction to form gasoline.
12. A process for producing a motor fuel having high anti-detonating qualities which comprises separating gasoline into lighter and heavier fractions, subjecting at least one of said heavier fractions to heat treatment at a temperature from 1000° F. to 1200° F. for a period of from two seconds to one minute whereby the anti-detonation characteristics of said fraction are increased solely by thermal conversion and blending the fraction so treated with a gasoline fraction to form gasoline.
13. The process of producing gasoline possessing superior anti-detonating characteristics as a motor fuel that comprises cracking a petroleum oil heavier than gasoline, primarily separating the resultant naphtha stock from higher boiling materials, secondarily separating by fractionation the higher boiling portions of said naphtha stock consisting mainly of hydrocarbons in the gasoline boiling range from the lower boiling portion thereof, passing the said separated higher boiling gasoline hydrocarbons through a heating coil wherein the gasoline constituents are subjected to a temperature of upwards of 850° F., separating the gasoline stock so produced from the other products of the last mentioned cracking reaction and commingling the said separated gasoline stock with the lower boiling hydrocarbons primarily separated from the said naphtha stock to produce an anti-detonating gasoline.
14. The process of producing gasoline possessing superior anti-detonating characteristics as a motor fuel that comprises cracking a petroleum oil heavier than gasoline, primarily separating the resultant naphtha stock from higher boiling materials, secondarily separating by fractionation the higher boiling portions of said naphtha stock consisting mainly of hydrocarbons in the gasoline boiling range from the lower boiling portion thereof, subjecting the said separated higher boiling gasoline hydrocarbons to heating at a temperature of upwards of 850° F. to effect a transformation of hydrocarbon constituents into products of increased anti-detonating value and separating from the resultant products of reaction a gasoline of high anti-detonating value.
15. The process of producing gasoline possessing superior anti-detonating characteristics as a motor fuel that comprises cracking a petroleum oil heavier than gasoline, primarily separating the resultant naphtha stock from higher boiling materials, secondarily separating by fractionation the higher boiling portions of said naphtha stock consisting mainly of hydrocarbons in the gasoline boiling range from the lower boiling portion thereof, subjecting the said separated higher boiling gasoline hydrocarbons to heating at a temperature of upwards of 850° F. to effect a transformation of hydrocarbon constituents into products of increased anti-detonating value, separating a gasoline stock from the resultant products of reaction and commingling the said separated gasoline stock with a gasoline fraction to produce and anti-detonating gasoline.
16. A process for increasing the anti-detonation characteristics of gasoline which comprises subjecting the gasoline to fractionation to separate it into fractions of higher and lower boiling points, subjecting a higher boiling fraction to heating at a temperature within the range of 850° F.-1200° F. for a period of time upwards of two seconds and not exceeding ten minutes to thereby effect solely by thermal conversion a transformation of hydrocarbon constituents into products of increased anti-knock value and separating from the resultant products of reaction a gasoline having a high anti-knock value.
17. The process of producing gasoline possessing superior anti-detonating characteristics as a motor fuel that comprises heating crude petroleum to effect vaporization of a naphtha stock and primarily separating the vaporized naphtha stock from the unvaporized portion of the crude petroleum, secondarily separating by fractionation a higher boiling portion of said naphtha stock consisting mainly of hydrocarbons in the gasoline boiling range from a lower boiling portion thereof, subjecting the said separated higher boiling gasoline hydrocarbons to heating at a temperature of upwards of 850° F. to effect a transformation solely by thermal conversion of hydrocarbon constituents into products of increased anti-detonating value and separating from the resultant products of reaction a gasoline of high anti-detonating value.

CERTIFICATE OF CORRECTION.

Patent No. 2,039,894.

May 5, 1936.

JOHN C. GENIESSE, ET AL.

It is hereby certified that error appears in the printed specification of the above numbered patent requiring correction as follows: Page 4, first column, line 8, claim 8, after "F." insert a comma; line 36, claim 11, for the word "of" read in; line 46, claim 12, after "temperature" insert of; and second column, line 27, claim 15, for "boling" read boiling; line 36, same claim, for "and" read an; and that the said Letters Patent should be read with these corrections therein that the same may conform to the record of the case in the Patent Office.

Signed and sealed this 25th day of August, A. D. 1936.

Leslie Frazer
